Application August 22, 1931, Serial No. 558,798

32 Claims.

(Cl. 66—24)

This invention relates to mechanisms for the production of knitted fabrics. It particularly relates to a knitting machine for the automatic knitting of ribbed or plain seamless hosiery, or other tubular fabrics without the necessity of manual transfer.

The primary object of this invention is the provision of an improved knitting machine whereon seamless knitted fabric may be knitted with both plain or ribbed effect with an automatic transferring of the fabric.

A further object of this invention is the provision of an improved knitting machine of the type generally disclosed in U. S. Patent #933,443, but which has associated therewith improved means for the knitting of plain and ribbed fabric, with improved means to automatically effect the transfer of the stitch loops of the fabric from dial needles of the machine to certain cylinder needles at the time of transfer from rib knitting to plain knitting.

In the accompanying drawings, forming a part of this specification, and wherein similar reference characters designate corresponding parts throughout the several views,

Figure 1 is a side elevation of the improved knitting machine.

Figure 2 is a fragmentary sectional view taken through the cylinder and dial parts of the improved machine, showing their cooperative relation and the drive means therefor.

Figure 3 is a front elevation of certain parts of the improved knitting machine.

Figure 3a is a developed view in a plane of the cooperative needle action of the improved machine, and the association of cylinder needles and cams therefor.

Figure 4 is a fragmentary side elevation of mechanism by means of which a cam controlling drum is operated with a step by step movement from the conventional "104" wheel of the Banner type of knitting machine, the parts being shown in an operative relation with said wheel.

Figure 5 is a view showing the parts of Figure 4 inoperatively positioned with respect to "104" wheel, and under which circumstances the cam controlling drum is stationary.

Figure 6 is a diagrammatic perspective view of the cooperative action of the cylinder and dial needles during the transfer of the stitch loops of the fabric being knitted when transferring from rib knitting into plain knitting.

Figure 7 is a plan view of a knitting machine dial with needles supported therein; dial cap cam parts being shown in dot and dash lines,

Figure 8 is a view of the cam structure of the dial cap; the latter being inverted from its normal position.

Figure 9 is a fragmentary view of the knitting machine from the rear thereof, showing more particularly the means for operating the cam controlling drum from the conventional "104" wheel, and the association of cam operating levers and rods with the drum.

Figure 10 is a fragmentary developed view on a plane surface of a part of the needle cam controlling drum, showing the operative association thereon of means for operating the various cam levers and parts.

Figures 11 to 18 inclusive are diagrammatic views of the cam drum showing the respective means thereon for operating the various needle cam operating levers and parts.

Figure 19 is a cross sectional view taken on the line 19—19 of Figure 1.

In the drawings, wherein for the purpose of illustration is shown only a preferred embodiment of the invention, the letter A may generally designate the machine, which includes a frame B, a cylinder C, a dial D, means E to operate the cylinder and dial. F may generally indicate a set of cylinder needles, and G a set of dial needles.

Generally the machine frame B includes a supporting bed 20 whereon the rotatable needle cylinder C is mounted. The means for rotating and oscillating the cylinder C are of any approved type, and preferably those shown in the patent above mentioned. The cylinder is driven from a main shaft 21, shown in Figure 9 of the drawings, whereon are positioned the usual pulleys and gearing including a pinion 22 for driving a larger gear 23 known conventionally as the "104" gear, which is suitably mounted upon a shaft 24. The main drive shaft is also provided with the usual quadrant 25 for reciprocating the cylinder during the knitting of the heel and toe, as is usual, and will be well understood by those skilled in this art.

The needle cylinder C is provided with the usual needle grooves 26 wherein the latch needles 45 of the set F are independently mounted for reciprocation. At its upper end the cylinder is provided with the usual web holding bed ring 15 whereon the web holders or sinkers 16 are reciprocably mounted within radial grooves; the 50 same being actuated during their radial movement by cams supported upon a cam ring 17 which is stationary during rotation of the cylinder.

The machine is of the independent latch needle 55

type, but it is to be understood that the improvements are not to be limited in application to the machine shown, nor to a latch needle type of machine except as limited by the scope of the 5 claims. There is provided a latch ring 28 pivotally supported at 29 upon a bracket 30 attached to the bed of the machine. Associated with the latch ring are one or more yarn fingers 31, shown in Figure 2 of the drawings, one of which 10 supports a body yarn 32 which is fed to the cylinder and dial needles for the production of plain or ribbed knitting. A second yarn finger 31^a may support another yarn 33, the purpose of which will be subsequently mentioned. These 15 yarn fingers are manipulated by the usual levers 34, shown in Figure 3 of the drawings, which in turn are operated from the pattern cam shaft 35, shown in Figure 3. This cam shaft is provided with the usual cams, ratchets, pattern 20 chain, etc. which are more particularly referred to in the patent above mentioned. The pattern chain 116 for purposes of the improvement to which this invention is directed, is provided with an operating lug 117, shown in Figures 4 and 5 25 of the drawings to control the operative or inoperative positions of the mechanism by means of which the needle cam control drum 94 is manipulated from the gear 23. Furthermore, the pattern cam shaft 35 is provided with a drum 40 30 directly keyed therewith.

On the rear of the bed 20 of the machine there is positioned an upwardly extending bracket 41 provided with a gear housing 42 overhanging the cylinder. This gear housing 42 rotatably supports a large gear 43 therein, to which is keyed a vertically positioned drive shaft 44. The latter is divided into an upper portion directly connected with the gear 43 and a lower portion 44^a keyed at 45 to the depending hub of the dial bed 46 of the dial construction D. The upper and lower parts of the dial drive shaft are connected by an intermediate drive link 48, which at its upper and lower ends is connected at 49 by universal joint with said upper and lower parts of the dial drive shaft. This drive shaft construction for the dial enables the latter to be driven truly concentric with the cylinder C. It is of course understood that the upper portion of the dial drive shaft 44 is splined on the gear 43, so that the shaft 44 may be slid upwardly, as is usual, to clear the dial from the top of the cylinder when necessary. The dial cap 50 is held in non-rotatable position above the dial bed by means of a two-part arm construction 51, consisting of a part 51^a bifurcated at its outer end and secured as shown at 52, see Figure 2 of the drawings, to the upwardly extending hub portion of the dial cap 50; the portion 51^a being connected to the other portion 51^b of the arm 51, as shown 55 in Figure 1, at 53. The portion 51^b has a sleeve 51^c slidable upon a vertical rod 54, which is secured at its upper and lower ends by means of brackets 55 secured to the standard 41. The sleeve 51^c slides freely along the shaft 54 between the clamps 55. In order to have access to the dial cap and turn the same the connection 60 65 53 may be removed.

The means E for driving the cylinder C includes a bevel gear 60 keyed to the lower end of the cylinder C, at 61. This bevel gear is of course driven in the usual manner off the drive shaft 21. The gear 43 of the dial drive shaft structure is driven off the gear 60. A vertical shaft comprising upper and lower parts 62 and 70 75 63 is provided, paralleling and spaced from the

cylinder C; the lower part 63 bearing at 64 in the bed 20 of the machine and having a pinion 65 keyed therewith and meshing with the gear 60. The upper portion 62 of the shaft has a pinion 66 keyed therewith and meshing with the gear 43; the gears 60 and 43 having the same pitch diameter, and the gears 65 and 66 having the same pitch diameter, so that the dial construction D is driven at the same speed of rotation as the cylinder C, for obvious reasons. Improved means adustably connects the shafts 62 and 63 so that they may be angularly adjusted and set with a desired adjustment to properly position the angularity of the dial construction D with respect to the cylinder C, so that the cylinder and dial needles will properly intermesh for rib knitting. To this end the upper and lower portions 62 and 63 of the drive shaft have complementary segment portions 68 and 69 connected therewith and keyed respectively therewith; the complementary segment extensions having adjusting screws 70 and 71 connected thereto, each of which may be adjusted in its segment to engage the chord face of the other segmental extension, to adjust the angularity of the shafts 62 and 63 with respect to each other, as will be apparent from Figures 1, 2 and 19 of the drawings.

Referring to the arrangement of latch needles comprising the entire needle set F for the cylinder C, as shown best in Figure 3a of the drawings the cylinder needles are all of the same length. Obviously any desired number of needles may be provided. As is usual, about one-half of the total number of these needles are provided with long butts, which have been designated in solid black on Figure 3a, and the remaining needles are provided with short butts which are properly indicated on the needles in Figure 3a, as will be obvious. The machine is provided with the usual narrowing pickers shown at 72 in Figure 3 of the drawings, and also provided with widening pickers which occupy the space 73 shown in Figure 3 of the drawings, but which have been omitted for the purpose of clarifying important details of the invention. These pickers are of the character set forth in the patent above referred to, and their functions are well understood by those skilled in this art.

Alternate latch needles of the set F are cooperatively placed in the same needle groove of the cylinder with long jacks 75, and the remaining needles have cooperatively associated in the respective grooves therewith short jacks 76. These jacks 75 and 76 are provided with butts which are arranged thereon according to the arrangement of long and short butts of the cylinder needles. Thus, one-half of the jacks 75 and 76 are provided with long butts which have been designated in solid black in the drawings; these long butts of the jacks being positioned beneath those cylinder needles which likewise have long butts. The remainder of the jacks 75 and 76 are provided with short butts shown in blank in Figure 3a.

As is usual, the dial bed 46 is provided with radial grooves within which the dial needles reciprocate. These dial needles are sub-divided into long and short butt needles; substantially one-half of them being long butts, as shown in black in Figure 7 of the drawings; the long butt dial needles being cooperatively and adjacently associated with the long butt cylinder needles.

Generally it will be understood that the dial needles are inoperative, so far as the knitting

yarn is concerned, during plain knitting; the cylinder needles doing all of the work. During rib knitting only alternate cylinder needles are elevated in position to take the knitting yarn; the remainder of the cylinder needles being sunk in the grooves and inoperatively positioned. Also during rib knitting the dial needles are provided in such association with the effective alternate cylinder knitting needles that there are two dial needles operative to take the dial stitch loop between the adjacent cylinder needles. That is, each stitch loop formed on the dial is received upon two of the dial needles, which holds it rather open. To effect the transfer of the loops from the dial needles to the cylinder needles which are ineffective during rib knitting, the dial needles with the stitch loops hung thereon are projected forwardly so that the stitch loops on the dial needles are positioned immediately over the ineffective cylinder needles, and the latter are then cammed through said loops; the stitch loops then being cast off the dial needles and onto the previously ineffective alternate cylinder needles. Thus, all of the cylinder needles will then be in position to proceed with plain knitting. This cooperative needle action is shown in the fragmentary needle perspective of Figure 6; it being shown in that view that the foremost dial and cylinder needles to the right are knitting ribbed work, and the transfer of the stitch loops from the dial needles to the previously ineffective cylinder needles is shown on the foremost needles to the left of the vertical center line of the axis of the dial.

35 A very compact mechanism is provided for operating the large number of cylinder and dial needle cams. It includes a plurality of operating levers 80, 81, 82, 83, 84, 85, 86, 87, 88, 89 and 90, shown in Figure 3 of the drawings, which are bent into substantially U or V-shape, so that the intermediate portions thereof may be placed in abutment and disposed upon a common pivot pin or extension 92 which is carried by the frame of the machine in the position shown in Figure 45 1 of the drawings. Each of the levers from this pivot 92 extends rather divergent with respect to the adjacent levers so that the outer ends of the levers both forwardly and rearwardly are relatively spaced, as is clearly shown in Figure 3. 50 These outer ends are adapted for receiving cam actuating links or levers, at either end thereof, as the case may be.

The levers 80 to 90 inclusive are actuated either by grooves or lugs placed upon the operating drum 94. The latter is rotatably mounted upon a suitable bolt or shaft 95 secured to an extension or side wall of the machine frame B, as shown in Figures 1, 3 and 8 of the drawings. The drum 94 is preferably hollow. It has an externally smooth circumference except adjacent to the frame of the machine where a rigid ratchet wheel is provided either integral or as an attachment therewith. The ratchet wheel is designated at 96 in the drawings and there are sixty teeth provided on it about the circumference of the drum.

Mechanism is provided for operating upon the teeth of the ratchet wheel 96 to produce a step by step advance in the rotary action of the drum 94; this mechanism being actuated off the gear wheel 23. Bearing in mind that the conventional "104" gear wheel 23 rotates once for every four revolutions of the cylinder C, it is intended that the drum 94 shall be advanced for the length of two teeth for one revolution of the

cylinder. That is accomplished by providing upon the drum facing side of the gear wheel 23 four laterally extending pins 97, which are positioned 60° apart on the gear wheel. That is, only 180° of the gear wheel is provided with the pins 97. The pins 97 each have rollers thereon which are in position to engage a pivoted lever 98. This lever 98 is keyed upon a shaft 99 bearing at 100 upon the rear of the frame B of the machine, as shown in Figure 9 of the drawings. Referring to Figures 4, 5 and 9 of the drawings it will be noted that the shaft 99 is also provided with another radially extending arm 101 keyed thereon, which intermediate its ends has a pivoted pawl 102 extending therefrom and at its free end resting by gravity upon the teeth of the ratchet wheel 96. A spring 103 is connected between the frame of the machine and the lever 101 and normally draws the latter into position so that the arm 98 will engage against the gear lugs 97 as the "104" gear rotates, as will be apparent from Figures 4, 5 and 9. Of course, rotation of the gear 23 will bring the lugs or pins 97 into engagement with the arm 98, throwing the latter rearwardly, and also moving the pawl 102 rearwardly, and incident to engagement of the pawl with the teeth of the ratchet wheel 96, as shown in Figures 4 and 5, the drum 94 will be advanced one tooth for each time that a pin or lug 97 engages against and moves the arm 98. Inasmuch as the four lugs 97 on the wheel 23 are positioned 60° apart, it is apparent that the drum 94 will be advanced the length of two teeth for one revolution of the cylinder.

In order to prevent continuous step by step rotation of the drum 94 after the cams have been put into proper operation either for plain or ribbed knitting, means is provided which will hold the pawl actuating lever 98 out of the path of movement of the pins or lugs 97. This mechanism includes a bell crank detent lever 105, pivoted at 106 on the side wall of the machine frame B, as shown in Figures 4 and 5 of the drawings; one end of the lever 105 at 107 being adapted for abutment with a surface 108 on the arm 101, as shown in Figure 5 of the drawings, to hold the lever 98 in position out of the path of engagement with the lugs 97. In this position the spring 103 will of course be further tensioned. This bell crank lever 105 at its opposite end is provided with a connecting rod 110 pivoted therewith at 111; the opposite end of the connecting rod 110 extending downwardly and being pivoted at 112 with the lower end of an arm 113. The latter is keyed on a shaft 114, rotatably bearing at 115, as shown in Figures 3, 4 and 5 of the drawings on the machine frame, at the front thereof. The pattern chain 116 is provided with a trip lug 117 adapted to operate against an arm 118 pivoted on a shaft 119. A leaf spring 120 normally urges the arm 118 against the pattern chain in the path of movement of the lug 117. The shaft 114 is furthermore provided with an arm 121 engaging against the arm 118. A spring 123 secured to the frame of the machine and the connecting rod 110 is under tension and normally urges the bell crank lever 105 into the position shown in Figure 5 and also urges the lever arm 121 against the arm 118.

To hold the detent bell crank lever 105 inoperative, as well as its associated mechanism, a bell crank lever 125 is provided, pivoted at 126 on the frame of the knitting machine. One end of this bell crank lever 125, namely 127, is in position to be engaged by pins or lugs 130 which

may be selectively placed at intervals on the drum 94. The other arm portion of the bell crank lever 125 is notched at 131 and 132, in stepped relation; these notches being adapted 5 to receive a pin 133 which is rigid upon a side of the bell crank detent lever 105.

As shown in Figure 4 of the drawings during step by step advance of the drum 94 the bell crank lever 125 is lowered at its end 127 to engage the drum periphery, and in this position the notch 131 receives the pin 133 to hold the bell crank lever 105 out of restraining relation with the arm 101, notwithstanding the action of the spring 123. In this position of parts the lug 117 10 will readily pass by the arm 118. In order to trip the arm 98 and throw it out of operating relation with the lugs 97, to stop a further step by step advance of the drum 94, it is necessary 15 to have a lug 130 so placed on the drum that it will ride against the concave face of the end 127 of the bell crank lever 125, so that the latter is rocked into the position shown in Figure 5, and at which instant the spring 123 will urge the bell crank lever 105 to the position shown in 20 Figure 5, abutting the end 107 against the edge 108 of the lever arm 101, and holding the arm 98 out of operating relation, as is quite apparent. The detent lever 105 is tripped from this position 25 by the lug 117 on the pattern chain 116, and at which time the pin 133 will engage in the lower notch 131 of the lever 125 to hold the bell crank detent lever 105 inoperative and permit the step by step actuation of the drum 94 to bring the lugs and grooves of the latter into needle cam 30 operating relation with associated lever mechanisms.

Referring to the cam arrangement on the dial cap 50 in connection with the dial needles as supported upon the bed 46, and referring to 40 Figures 7 and 8 of the drawings, the under-surface of the dial cap is provided with substantially concentric major inner and outer grooves 135 and 136, wherein are received the butts of the dial needles. The bed of the dial rotates in 45 the direction shown by the arrows in Figures 7 and 8 of the drawings, and it is especially apparent from Figure 7 of the drawings that when the butts ride in the inner groove 135 the dial needles will be inoperatively retracted in the dial bed, and it is only when riding in the groove 50 136 that the butts are positioned to be thrown into operating engagement with certain transfer and cast-off stitch cams 140 and 141. These cams 140 and 141 are stationary upon the dial 55 cap structure, but there are three cams 142, 143 and 144 which are vertically movable upon the dial cap for the purpose of guiding the butts of the dial needles from the groove 135 into the groove 136 or vice versa. Furthermore, the dial 60 cap also supports a vertically reciprocating latch closing cam 145 which is adapted to hold the needle latches closed during the projecting of the stitches held on the dial needles preparatory to a cast-off onto the cylinder needles to effect a 65 transfer from rib knitting to plain knitting. A cam extension 135^a throws the needle butts from the inner groove 135 to the outer groove 136 after one dial revolution.

The cams 142 to 145 inclusive are respectively 70 provided with spring actuated plungers 146, 147, 148 and 149, reciprocably supported in vertical sleeve-like housings 150^a, and of the construction shown in Figure 2. The springs thereof normally urge the plungers upwardly and of course 75 draw the cams to normally inoperative positions.

The plungers 146 to 149 inclusive, which respectively are associated with the cams 142 to 145, are in turn respectively associated with actuating levers 150, 151, 152 and 153, which are of identical construction. The latter levers are all 5 pivoted on a common pivot pin 154 supported on a bracket 155 which is rigid with the arm 51 above described, as is shown in Figure 1. The ends of the levers 150 to 153 inclusive, at the opposite sides of the pivot axis 154 from the ends 10 which engage their respective cam plungers, are respectively acted upon by vertically reciprocating links or levers 156 to 159. These levers at their upper ends are supported for vertical guiding in a bracket arm 160 connected on the standard 15 41, as shown in Figure 1. Intermediate their ends they extend through a suitable opening in the bed of the machine and at their lower ends they are respectively pivoted to the rear ends of the drum operated levers 85, 83, 84 and 82, as is 20 shown in Figure 9 of the drawings. The remainder of the cam operating levers, cam structures, and control means will be described as the operation of the machine is outlined.

During plain knitting, as above mentioned, the 25 dial needles are inoperative so far as the knitting yarn is concerned, and the only cams that are operative are the main knitting cams 170, 171, and 172, which are conventionally carried on the main cam block 173; the cams being shown 30 in Figures 3 and 3a of the drawings. In referring to the needle and cam action of the cylinder as diagrammatically illustrated in the developed view of Figure 3a it should be noted that the right hand portion, as designated shows the parts 35 during the knitting of rib work, and the left hand portion shows the parts in position at the start of transfer from rib knitting to plain knitting.

Continuing the description of the knitting 40 operation during plain knitting, as above mentioned, cams 170, 171 and 172 are operative, and the butts of the cylinder needles ride along the cam edge 174 after the knitting operation takes place. During plain knitting all of the cylinder 45 needles take the body yarn 32.

Plain knitting may continue as long as desired, according to the pattern, and at this time the cam drum 94 is not rotating since the lug or projection 130 on the drum 94 has moved the lever 125 50 into the position shown in Figure 5 of the drawings, thus inoperatively positioning the advancing pawl mechanism for the drum. As soon as plain knitting has been finished on the article being knitted, the pattern control chain lug 117 trips 55 the lever 105, through the sequence above described, again setting the pawl mechanism of the drum in operating relation to the lugs 97, for step by step advancement of the drum. In going from plain knitting into rib knitting the first 60 step is to clear the latches of the cylinder needles. This is done through elevation of the cam 175, shown in Figure 3a of the drawings. This latch clearing cam is of conventional nature and it is elevated off the pattern shaft drum 40, by means 65 of a lever 176 pivoted at 177. This lever 176 has a spring 178, and thru a connecting rod 179 the latch clearing cam may be moved to a latch clearing position with the cylinder needles, which is permitted as soon as the outer end of the lever 70 176 engages a cam 180 provided therefor on the pattern shaft drum 40, as shown in Figure 1. Thus, all of the cylinder needles are elevated to clear the latches over the stitches hung thereon. In the next operation the jack cam 181 is brought 75

into operation simultaneously with a pair of cams 182 and 183; the latter pair being mounted on the same block 184, as shown in Figure 1 of the drawings. The jack cam 181 is mounted upon a slide block 186 for radial sliding upon the bed of the machine, being spring urged at 187^a into normal operating position. The slide block 186 is operated upon by a bell crank lever 187 which is connected to a rod 188 attached to the drum actuated lever 90. The cam block 184 is actuated by a bell crank lever 189 which is connected with a link 190 secured to the forward end of the drum actuated lever 89, as is shown in Figures 1 and 3 of the drawings. The drum actuated levers 89 and 90, at their rear ends, as shown in Figure 9 of the drawings and elsewhere, normally ride upon segmental ribs 192 and 193, which are provided with certain depressions 194 and 195 respectively, into which the rear ends of the levers 89 and 90 drop to permit the raising of the fore ends of the levers 89 and 90 and the inward movement of the cams 181, 182 and 183 into operative relation with the jack and needle butts of the cylinder. The cam 181 is in position to take the butts of only the short jacks 76, starting with the long butts. It elevates all of the short jacks 76 and thus pushes the alternate cylinder needles upwardly so that their butts will ride against the uppermost cam 182. The remaining cylinder needles remain in place and their butts are engaged by the cam 183. The needles engaged by the latter cam are lowered so that their butts will ride against an inner cam edge 197 of the needle support ring 198, which is shown in dotted lines in Figure 3 of the drawings, thus lowering these alternate cylinder needles to an inoperative position in the cylinder; the ring 198 having an annular groove 199, shown in dotted lines in Figure 3a of the drawings, for reception of the cylinder needle butts during rib knitting. This position is well shown in the right hand portion of Figure 3a. The cylinder needles whose butts ride against the cam 182 are of course returned to a position where they are operated upon by the knitting cams. Any suitable means may be used to prevent unraveling, due to dropping of stitches from those cylinder needles which are buried, as above mentioned, such as the use of a crowding yarn. Cams 175, 181, 182 and 183 are then withdrawn from operation on the needles and jack butts. The dial cam 142 is lowered; the drum operating lever 85 thereof first being operated upon by the low portion 200 of a drum lug 201 for depressing the dial cam 142 sufficiently to first operate on the long butts of the dial needles. This cam 142 throws the dial needle butts from the groove 136 into position so that they are engaged by the cast-off cam 141 which projects the latch needles of the dial into position for receiving the main body yarn 32, as shown at the right hand portion of Figure 6 of the drawings. Knitting is effected when the dial needles are retracted at the portion 202 of the dial cam, as can readily be understood from Figures 6, 7 and 8 of the drawings. Rib knitting is now being effected on one-half of the cylinder needles, that is, the alternate needles, and in cooperation with all of the dial needles, and it should be noted that during rib knitting, shown at the right hand portion in Figure 6 of the drawings, each dial stitch loop 205 is held on two of the dial needles; there being thus two operative dial needles in the space between the effective cylinder needles during rib knitting.

75 Rib knitting is continued as long as desired,

since a stop lug 130^a is positioned on the drum 94, which immediately after manipulation of the cams for bringing rib knitting into play, will trip the detent lever 125 and permit the bell crank lever 105 to assume the position shown in Figure 5 for holding the pawl 102 inoperative, and thus preventing step by step rotation of the drum until the pattern chain again brings a lug similar to 117 into operation for tripping the lever 105.

When rib knitting of the article has been completed, and the pattern control mechanism has again thrown the pawl 102 into operative association with the wheel 96, a cam 210 is thrown into position to engage the butts of the alternate cylinder needles which were previously effective 10 during rib knitting, as is shown in Figure 3a of the drawings. This cam 210 is mounted in a cam block 211 and normally spring urged out of operation. The cam 210 is operatively connected with a bell crank lever 212, and the latter in turn 20 is connected by a rod 213 with the rear end of the cam drum actuated lever 81. As shown in Figures 10 and 17 of the drawings the drum 94 has a lug 214 thereon, a low portion 215 of which first engages the lever 81 for the purpose of 25 throwing the cam 210 into position to first engage the long butts of the cylinder needles, and thereafter as the lever 81 rides upon the higher portion of the drum lug 214 the cam 210 will be thrown into operation to engage the alternate 30 shorter butt needles. The cylinder will rotate twice with the cam 210 effective upon the needle butts, and it is to be noted that the cam 216 will bring these alternate needles, which were 35 previously ineffective during rib knitting, back into position to be operated upon by the knitting cams. Immediately after the alternate cylinder needles have been lowered by the cam 210 the latch holding cam 145 is lowered into effective 40 latch holding relation with the dial needles, and simultaneous therewith the dial cams 143 and 144 are depressed into needle butt engaging relation with the dial needles. Also simultaneous with the effective bringing into play of the cams 143, 144 and 145 there are brought into effective 45 jack butt engaging relation a pair of cams 220 and 221. The latter two cams are mounted upon a single supporting block 222, which is actuated by a bell crank lever 223, as shown in Figures 1 and 9 of the drawings; the said bell crank lever 50 being operatively connected with the drum actuated lever 80 by a connecting rod 224. The dial cam 143 is depressed, for the purpose of throwing the dial needles radially outward in cooperative relation with the latch closing cam 145, 55 which is also simultaneously lowered, and also in cooperation with the cast-off stationary cam 140 shown in Figures 7 and 8 of the drawings. As will be noted, the cam operating drum 94 is provided with a lug 230, see Figures 10 and 15, 60 which has a low portion 231 at the advancing side which first comes into engagement with the lever 83 rocking the same, and through the connecting rod 151 operating the plunger mechanism for depressing the cam 143 so that the 65 long butts of the dial needles are engaged first, and thereafter the higher portion of the lug 230 further depresses the cam to take the short butts of the dial needles. Noting from Figures 6 and 7 that the latches of the dial needles are closed, 70 as shown at 233 in Figure 6 of the drawings, the cam 143 projects the needles with the latches closed radially outward. The cam 145 has been lowered, as above mentioned, to maintain these 75 latches of the dial needles closed, as they project

radially outward, so that the stitch loops hung on the pairs of dial needles may be projected under tension radially outward to position then directly over the alternate cylinder needles which 5 are buried and inactive during rib knitting. This cam 145 is operated off the lug 234 on the drum 94, as shown in Figures 10 and 16, and elsewhere; the lug 234 operating the lever 82 and through the connecting link 151 operating the 10 plunger mechanism of the cam 145 for lowering the latter to the position shown in Figure 1 of the drawings. As the dial bed rotates the dial needles with their latches closed are projected beneath the cam 145 and the latches are 15 held closed by the latter until the stitch loops, shown at 237 in Figure 6 of the drawings are directly over the alternate cylinder needles, which were previously inactive during rib knitting, and which cylinder needles are now elevated through 20 action of the cams 220 and 221 to slip within the respective loops 237. With the cylinder needles within the stitch loops 237, as shown in Figure 6, the dial needles are projected radially outward by riding against the cam 140 until 25 the latches ride off the cam 145, and at which time since the stitch loops are tensioned, the latches spring open, as shown in Figure 6 and the loops 237 slip backwardly over the open latches. The dial needles are then retracted to 30 cast off from the loops 237; these loops then being hung on the alternate cylinder needles. This transfers the stitch loops from the dial needles to the cylinder needles and the cams and needles may now be manipulated as previously explained 35 for plain knitting.

Referring to the operation of the cams 220 and 221, and referring to Figure 3a of the drawings, it will be noticed that the cam 220 operates on the butts of the long jacks and elevates them to a 40 position where the cam 221 may operate on the butts of both the short and long jacks. Inasmuch as the cam 221 brings the butts of all of the jacks, both long and short, to the same level, it will be quite apparent from Figure 3a of the 45 drawings that the previously inactive cylinder needles buried in the cylinder grooves during rib knitting will be projected upwardly through the plane in which the dial needles lie, and as above described for the purpose of slipping them 50 through the stitch loops 237 of the yarn hung on the dial needles. Of course, the cam 221 only elevates the cylinder needles which are beneath the short jacks to a position where their hooks lie below the plane in which the dial needles 55 lie.

As above mentioned the cams 220 and 221 are on the same block 222; the drum 94 being provided with a lug 240 which operates a lever 80 to which the connecting rod 224 is affixed.

Referring to Figures 7 and 8 of the drawings it is to be noted that after the transfer operation the dial needles are prevented from taking new yarn. The cam 144 is instrumental in retracting the needles, as it is lowered simultaneous with the cams 143, 145, 220 and 221. It first engages the long butts of the dial needles and throws the butts into the inner groove 135 of the dial cam construction, as shown in Figure 7, thus preventing the dial needles from radially extending to take the new knitting yarn. Immediately thereafter the cam 142 is elevated out of the path of the dial needle butts, by reason of the fact that the lever 85 rides off the lug 201, so that the short butt dial needles pass by 75 the cam 141 without being projected.

The drum 94 is provided with a lug 242 which operates the lever 84 for the purpose of depressing the dial cam 144, as will be obvious from the drawings. From Figure 10 it will be apparent that the starting ends of the lugs 230, 234, 240, and 242 are all in the same line for simultaneously actuating the dial cams 143, 144, and 145, as well as the cylinder jack cams 220 and 221.

It is to be noted that the latch holding cam 145 really cooperates with the latch ring 28 of the machine in holding the latches closed until the dial needles are opposite a notch 245, on the latch ring 28, shown in Figure 1 of the drawings, and at which time the latches of the dial 15 needles spring open due to tension of the stitch loops 237 thereon, and thus the dial needle stitch loops 237 ride back against the elevated cylinder needles, as shown in the left hand portion of Figure 6 of the drawings. 20

Subsequent to the above operation the cylinder needles are next actuated by the cam 216, as usual; said cam 216 operating on the butts of all of the cylinder needles, and of course they take the new knitting yarn and are actuated by 25 the knitting cams in conventional manner to produce plain knitting.

Thereafter the lug 130^a of the drum will ride into engagement with the trip lever 125 for throwing the advancing pawl out of operation 30 until the latter is tripped into operation by the pattern chain, as above described.

If desired both round and tuck welts may be knitted with my machine.

It is to be noted from Figure 1 that springs 94^a hold each of the levers 80 to 90 inclusive into engagement at their rear ends with the drum 94.

During plain knitting the dial needles are of course retracted. At the start of rib knitting, 40 when the cam 142 is lowered, the dial needles are projected, with their latches closed. To open the latter, so that the dial needles may receive the knitting yarn, a brush 251 has been provided. It is mounted detachably at 252 (see Figure 3) 45 on the latch ring, and has hair bristles into which the dial needles project, and which throw the latches open as the dial needles are farther moved in a projecting relation.

It is to be distinctly understood that reference in the specification and particularly in the claims, to "plain knitting", "plain knitted fabric", "plain fabric" is intended to characterize any kind of knitting that may be accomplished upon the cylinder needles, or upon the cylinder needles with part of the dial needles in contradistinction to rib knitting. Such terms are merely intended to serve as an index in characterizing a change from rib knitting to another kind of knitting, or vice versa, effected automatically, that is, without stopping the machine and manually effecting the transfer. Thus, "plain knitting" may embody the knitting of fabric having tuck, mesh, or drop stitches, and may include also the knitting of fabric with plating yarns either normally plated, striped, or reverse plated in designs. 55 60 65

Reference is also made in the specification and claims to means for holding the dial needle latches "closed" in order to project the stitch loops into transferring relation with the cylinder needles. The term "closed" is not to be construed as limiting the operation to a complete shutting of the latches, since the latches may 70 75

remain partially open and still effect the desired result.

Various changes in the shape, size, and arrangement of parts may be made to the embodiment 5 of the improved knitting machine herein described within the scope of the claims.

I claim:

1. In a knitting machine for automatic transfer from rib knitting to plain knitting the combination of a dial, a cylinder, latch needles, and operating devices therefor including means to transfer from rib knitting to plain knitting, said means comprising means to hold the latches of the dial needles closed while the latter are projected to extend the respective yarn loops of the fabric being rib knitted which are hung thereon to positions over the subjacent cylinder needles, means to extend the said cylinder needles through said loops as thus held by the closed 15 latch needles, and means subsequently operating the dial needles to cast off said loops onto the cylinder needles.

2. In a knitting machine the combination with a cylinder and cylinder needles, a dial and dial 25 needles, means for actuating all of the cylinder needles and inoperatively positioning the dial needles to produce plain knitting upon the cylinder needles, the cylinder needles being provided in substantially the same number as the 30 dial needles and in intermeshing yarn receiving relation therewith, and means to automatically proceed from plain to rib knitting upon said cylinder and dial needles including means to bury the alternate cylinder needles in the cylinder in 35 inactive relation so that the yarn during rib knitting is looped upon the remaining cylinder needles and all of the dial needles with each dial stitch loop hung on a pair of the dial needles between the adjacent effective cylinder needles.

40 3. In a knitting machine the combination with a cylinder and cylinder needles, a dial and dial needles, means for actuating all of the cylinder needles and inoperatively positioning the dial needles to produce plain knitting upon the cylinder needles, the cylinder needles being provided in substantially the same number as the dial 45 needles in intermeshing yarn receiving relation therewith, means to produce rib knitting upon said cylinder and dial needles including means to bury the alternate cylinder needles in the cylinder in 50 inactive relation so that the yarn during rib knitting is looped upon the remaining cylinder needles and all of the dial needles with each dial stitch loop hung on a pair of the dial needles between the adjacent effective cylinder needles, and 55 means to effect a transfer of the stitch loops from the dial needles to the alternate cylinder needles which are inactive during rib knitting including means to project the dial needles and the stitch 60 loops hung thereon into position over the cylinder needles which are inactive during rib knitting and elevating the latter cylinder needles into the stitch loops of the dial needles, and casting off the stitch loops from the said dial needles.

65 4. In a knitting machine, two sets of needles, operating means therefor to produce ribbed or plain knitted fabric, said operating means including means to knit plain fabric on one of said sets of needles, means to knit ribbed fabric on all of 70 the needles of the second set and the alternate needles of the set on which the plain fabric is knitted, and means for direct projection of the 75 stitches by the needles of the second set into position to receive in the stitch loops thereof the said alternate needles of the first set which are in-

active during rib knitting when transferring from rib knitting to plain knitting.

5. In a knitting machine the combination of a set of cylinder needles, a set of dial needles, said dial needles being projected in pairs side by side 5 through the spaces between adjacent effective cylinder needles during the knitting of ribbed work so that the stitch loops of the fabric being knitted are hung from the dial needles, with each pair of dial needles receiving a single stitch loop 10 of the fabric yarn, and means for transferring the stitch loops from the pairs of dial needles to the cylinder needles when transferring from rib knitting to plain knitting.

6. In a knitting machine the combination of a 15 set of cylinder latch needles, a set of dial latch needles, means cooperatively manipulating the said cylinder and dial needles for the knitting of ribbed work during which the alternate cylinder needles only are active in the knitting operation 20 with a pair of dial needles cooperating between the adjacently spaced effective cylinder needles, the remainder of the cylinder needles being buried and in position to be elevated in the spaces between the pairs of dial needles cooperating with 25 the adjacent cylinder needles which are effective during ribbed knitting, and means to manipulate the dial needles, and the cylinder needles which are ineffective during ribbed knitting, to transfer the stitch loops of the fabric from the pairs of 30 dial needles to the previously ineffective cylinder needles to effect an automatic transfer from rib knitting to plain knitting.

7. In a knitting machine the combination of a 35 set of cylinder latch needles, a set of dial latch needles, means cooperatively manipulating the said cylinder and dial needles for the knitting of ribbed work during which the alternate cylinder needles only are active in the knitting operation 40 with a pair of dial needles cooperating between the adjacently spaced effective cylinder needles, the remainder of the cylinder needles being buried and in position to be elevated in the spaces between the pairs of dial needles cooperating with 45 the adjacent cylinder needles which are effective during ribbed knitting, means to manipulate the dial needles, and the cylinder needles which are ineffective during ribbed knitting, to transfer the stitch loops of the fabric from the pairs of dial needles to the previously ineffective cylinder 50 needles to effect an automatic transfer from rib knitting to plain knitting, said last mentioned means including means to hold the latches of the dial needles closed for projection of the dial needles and the stitch loops thereon into position 55 with the stitch loops located to directly receive therein the cylinder needles cooperatively located therebelow when elevated to effect the transfer.

8. In a knitting machine the combination of a set of cylinder needles, a set of dial needles of the 60 pivotal latch type, and means to transfer stitch loops from the dial needles to the cylinder needles including cam means for holding the latches of the dial needles closed and for projecting the dial needles outwardly to position the stitch loops 65 hung on the dial needles in an open cylinder needle receiving relation.

9. In a knitting machine the combination of a cylinder, a dial, a set of cylinder needles, a set of 70 dial needles, means to drive the cylinder, and means synchronized with the last mentioned means to drive the dial including a universal jointed connection to permit the dial to rotate in a concentric relation with the cylinder.

10. In a knitting machine the combination of a 75

- cylinder, a dial, a set of cylinder needles, a set of dial needles, means to drive the cylinder, means synchronized with the last mentioned means to drive the dial including a universal 5 jointed connection to permit the dial to rotate in a concentric relation with the cylinder, said dial drive means including means for angularly adjusting the dial with respect to the cylinder to effect minute angular adjustments between the 10 cylinder and dial.
11. In a knitting machine the combination of a cylinder, a dial, cooperative cylinder and dial needle sets, means for manipulating the needles for the production of knitted fabric, means for 15 rotating the cylinder, and means for synchronously driving the dial with the cylinder including a flexible drive connection which will automatically permit the dial to preserve its concentricity with the cylinder.
- 20 12. In a knitting machine the combination of a cylinder, a set of cylinder latch needles, a dial, a set of dial latch needles, means for inactively positioning the dial needles and actively positioning the cylinder needles to effect plain knitting 25 upon the latter, pattern controlling means for rendering all of the dial needles active and rendering the alternate cylinder needles inactive for the production of rib knitted fabric upon the remaining cylinder needles and the dial needles, means 30 for automatically transferring the stitch loops from the dial needles to the cylinder needles which are inactive during rib knitting, including means to project the dial latch needles with the latches closed until the stitch loops hung thereon 35 are positioned in open relation over the adjacent cylinder needles which are inactive during rib knitting, means for elevating the said cylinder needles which are inactive during rib knitting through the open loops of the dial needles as held 40 by the last mentioned means, and means further manipulating the dial and cylinder needles for casting off the stitch loops from the dial needles onto the said alternate cylinder needles which were previously inactive during the rib knitting 45 operation.
13. In a knitting machine for the automatic knitting of plain or ribbed fabric a cylinder including a set of needles, a dial including a set of latch needles, cam means or the dial for projecting the dial needles into yarn receiving and knitting relation, means for rendering the last mentioned cam means inactive with respect to said dial needles, other cam means for projecting the dial needles with the stitch loops hung thereon 50 radially outwardly, and cam means associated with the last mentioned means for holding the latches closed as they are projected by the last mentioned means for projecting the yarn loops hung thereon outwardly to a desired cylinder 55 needle receiving position.
14. In a knitting machine for the automatic knitting of plain or ribbed fabric a cylinder including a set of needles, a dial including a set of latch needles, cam means on the dial for projecting the dial needles into yarn receiving and knitting relation, means for rendering the last mentioned cam means inactive with respect to said dial needles, other cam means for projecting the dial needles with the stitch loops hung thereon 60 radially outwardly, cam means associated with the last mentioned means for holding the latches closed as they are projected by the last mentioned means for projecting the yarn loops hung thereon outwardly to a desired cylinder needle receiving 65 position, and means to inoperatively retract all of the dial needles at a position succeeding the last mentioned means.
15. In a knitting machine for automatically knitting plain and rib fabric and for the automatic transfer of one to the other the combination of a frame, a rotatable cylinder on the frame, a set of cylinder needles, a dial, a set of dial needles, a set of operating cams for the cylinder, a set of depressible cams for the dial, a cam controlling drum, a set of levers mounted on a common pivot in operative association with the drum, means for step by step advancement of the drum, means for automatically tripping the last mentioned means, and connecting means between the said levers and the various cylinder and dial cams for cooperatively operating said cams. 10
16. In a knitting machine dial cam construction the combination of a dial cap having a pair of substantially concentric inner and outer butt receiving grooves therein, a needle projecting cam for projecting the needles to yarn receiving position located in cooperative association with the outer groove, a movable cam for selectively deflecting the butts of the needles against the last mentioned cam, a knitting cam, a cam in the path of the inner groove for deflecting the butts of the needles into the outer groove, a movable cam associated with the outer groove for deflecting the butts of the needles into the inner groove, a needle projecting cam spaced from the knitting cam for projecting the needles to a latch shedding position, a movable cam associated with the outer groove and with the last mentioned cam for selectively directing the butts of the needles onto the last mentioned cam, said movable cam which is positioned to deflect the butts of the needles from the outer to the inner groove being positioned to receive the butts of the needles after they have passed the latch shedding cam, and a latch closing cam in position to hold the latches closed as they are fed outwardly by the latch shedding cam. 15
17. In a knitting machine for the production of ribbed or plain knitted fabric and for the automatic transfer of one to the other, the combination of a cylinder having grooves therein, a set of cylinder needles operative in said grooves, a set of short jacks in said grooves beneath the alternate cylinder needles, a set of longer jacks in the grooves beneath the remaining cylinder 20 needles, a dial and a set of dial needles, means for manipulating all of the cylinder needles for the production of plain knitting, cam means actuating the jacks and needles for alternately dividing the cylinder needles so that the cylinder needles with the longer jacks therebeneath are inactively buried in the cylinder during a rib knitting operation, means for manipulating the alternate elevated cylinder needles which have the shorter jacks therebeneath in combination 25 with all of the dial needles for the production of rib knitted fabric, the dial needles with such arrangement having a pair of each operating in the spaces between the effective adjacent cylinder needles and in side by side relation, whereby the loops on the pairs of dial needles will be held in a spread relation, means to hold the latches of the dial needles closed when projecting the dial needles with the loops hung thereon outwardly to position the open loops held 30 thereon directly over the buried cylinder needles which are ineffective during rib knitting, cam means for elevating said last mentioned cylinder needles into the open loops of the yarn held on the dial needles, and means for subsequently 35
- 40
- 45
- 50
- 55
- 60
- 65
- 70
- 75

manipulating the dial needles and cylinder needles to shed the stitch loops from the dial needles and transfer them to the cylinder needles for the resumption of plain knitting.

5 18. In a machine for the automatic transfer of knitted fabric from rib knitting to plain knitting the combination of a set of needles, means for manipulating said set of needles for the production of plain knitting, a second set of 10 needles, means for manipulating both of said sets of needles for the production of rib knitting wherein alternate loops of the fabric in the course being knitted are held upon needles of the first set and the remaining loops of the fabric in the 15 course being knitted are each held on relatively spaced pairs of needles of the second set with each loop distended, and means for manipulating said sets of needles to transfer the loops of the second set to needles of the first mentioned set 20 by which the needles of the first set are projected through the loops held on pairs of needles of the second set and said loops transferred therefrom.

19. In a knitting machine for knitting plain and ribbed fabric and for transferring from 25 ribbed fabric to plain knitted fabric automatically, the combination of a set of cylinder needles, a set of dial needles, means for manipulating said sets whereby during ribbed knitting alternate loops of the fabric in the course being 30 knitted are held on alternate cylinder needles and the remaining loops on the dial needles with each of the last mentioned loops on a pair of relatively spaced dial needles to hold said loops laterally distended, and means to project the 35 remaining cylinder needles through the distended loops held on the pairs of dial needles and freeing the loops of the dial needles to transfer them to the said remaining cylinder needles.

20. In a knitting machine the combination of 40 a set of cylinder needles, a set of dial needles, said dial needles being projected in pairs side by side thru the spaces between effective cylinder needles during the knitting of ribbed work so that each alternate stitch loop of the fabric being 45 knitted during rib knitting is hung upon a pair of relatively spaced side by side dial needles, and means for transferring the stitch loops from the pairs of dial needles including means to elevate the respective cylinder needles 50 between the needles of an adjacent pair of dial needles through the stitch loop hung thereon, and means to cast the stitch onto the cylinder needle.

21. In a knitting machine the combination of 55 a set of cylinder needles, a set of dial needles of the latch type, and means to transfer stitch loops from the dial needles to the cylinder needles including cam means for holding the latches of the dial needles closed with the stitch loops directly 60 on the needles and for projecting the dial needles outwardly to position the stitch loops as so hung on the dial needles in an open cylinder needle receiving relation.

22. A knitting machine for knitting fabric 65 partly ribbed and partly plain, having two needle carriers, ever active and occasionally active needles recurrently interspersed in one carrier, and pairs of laterally spaced needles in the other carrier corresponding to the occasionally 70 active needles, in combination with means for knitting ribbed work upon said ever active needles and the pairs of laterally spaced needles so that each of said pairs of laterally spaced needles receives a stitch loop in laterally distended relation thereon, means for projecting the occa-

sionally active needles between the needles of the pairs of laterally spaced needles respectively associated therewith and into the respective distended stitch loops thereon, and means for casting the loops off said pairs of laterally spaced 5 needles onto the respective occasionally active needles inserted in the stitch loops thereon.

23. In a knitting machine the combination of a set of needles, a second set of needles, carrier means for cooperatively receiving said sets of 10 needles, both of said sets of needles being of the latch type, and means to transfer stitch loops from the first set of needles to the second set of needles including means to hold the latches of the first set of needles closed and to project the 15 needles and the respective stitches thereof into stitch transferring relation with the needles of the second set.

24. In a knitting machine the combination of a set of needles, a second set of needles, carrier 20 means for cooperatively receiving said needles for relative movement, means for manipulating the first set of needles so that stitch loops thereof are each held on relatively spaced pairs of needles which are independently movable longitudinally 25 and laterally with respect to each other, and means for manipulating the needles of both sets for transferring the loops hung on the pairs of needles of the first set to the needles of the 30 second set.

25. In a knitting machine the combination of a cylinder having a set of needles therefor, a dial having a set of needles therefor in cooperative knitting relation with the needles of the cylinder, and means for synchronously rotating the cylinder and dial including a drive shaft for the dial arranged substantially axially of the cylinder and having a universal joint connection 35 therein between the driven end of said shaft and said dial.

26. In a knitting machine a set of needles, a second set of latch needles, cam means for projecting the latch needles of the second set into yarn receiving and knitting relation with the needles of the first set, other cam means for projecting the latch needles of the second set with the stitch loops hung thereon into stitch transferring relation with the needles of the first set, cam means associated with the last mentioned cam means for holding the latches 50 of the second set of needles closed as they are projected by said last mentioned cam means in order to position the loops thereon into needle receiving relation with the needles of the first set, and means for actuating the needles of both 55 sets to effect such transfer.

27. In a knitting machine the combination of a set of latch needles, a second set of latch needles, carrier means for the latch needles of both sets, and means to effect the transfer of 60 stitch loops from the first set of needles to the needles of the second set including a cam to project the needles of the first set into stitch transferring relation with the needles of the second set, a cam for holding the latches of the 65 needles in the first set closed during such projection to tension the stitch loops and move them into transfer position with the needles of the second set of needles, and means to project the needles of the second set into the stitch loops as 70 thus positioned.

28. In a knitting machine the combination of a set of cylinder needles, a set of dial needles, said dial needles being projected in pairs side 75 by side above the spaces between the effective

- cylinder needles during the knitting of ribbed work so that each alternate stitch loop of the fabric is hung upon a pair of relatively spaced side by side dial needles, means for projecting 5 said pairs of dial needles radially outward, means for holding the latches of the dial needles closed as they are thus projected outward until the stitch loops are tensioned thereagainst and positioned in transferring relation with the respective 10 cylinder needles associated therewith, means to elevate the respective cylinder needles between the needles of an adjacent pair of dial needles thru the stitch loops hung thereon, the tensioned stitch loops opening the latches when the means 15 holding the dial needle latches closed is passed, and means to further project the dial needles to cast off the stitches hung thereon onto the respective cylinder needles.
29. In a knitting machine the combination of 20 a set of latch needles, a second set of latch needles, means to knit fabric upon the needles of both of said sets, and means to automatically transfer the stitch loops from one of said sets to the other set including means to hold the 25 latches of the first set of needles in position to prevent slipping of the stitch past the latch during needle projection, means to project the needles with the latches holding the stitches as aforesaid into stitch transferring relation with 30 the needles of the second set, and means to effect said transfer by releasing the said latches and casting the stitches off the said needles of the first set.
30. In a knitting machine two sets of latch 35 needles, means to effect knitting upon both of said sets of needles, means to effect knitting on only one of said sets, and means to automatically transfer stitch loops from one of said sets

of needles when changing from the knitting on both sets of needles to the other set of needles including means to project said needles of the two sets into stitch transferring relation, and means holding the stitches against cast-off 5 directly by the latches of that set of needles from which the cast-off is to be made until the needles of the other set are in respective stitch transferring relation within the stitch loops hung upon the respective needles from which the 10 stitches are to be cast off, and subsequently casting the stitches off the latches and needles thereof onto the needles which have been placed in stitch transferring relation therewith.

31. In a knitting machine for automatically 15 transferring from rib knitting to another type of knitting, the combination of two sets of latch needles, operating devices therefor including means to transfer from rib knitting to said other type of knitting and vice versa, said means comprising means to hold the latches of one of said sets of needles in position to prevent slipping of the 20 stitch loop hung thereon past said latches while the said needles whose latches are so held are projected to extend the stitch loops hung thereon into transferring relation with the respective needles of the other set, and means to complete said transfer of the stitch loops by casting off the stitch loops onto the other needles.

32. In a knitting machine the combination of 25 two sets of needles, two rotatable carriers, one for each set of needles, means to drive one of said carriers, and means synchronized with the last mentioned means to drive the other carrier including a universal jointed connection to permit the last mentioned carrier to rotate in proper 30 position with respect to the other carrier.

HARRY McADAMS.
